UNITED STATES PATENT OFFICE

2,447,986

DEVELOPING RACK

Herman Millman, Brooklyn, N. Y.

Application June 23, 1945, Serial No. 601,215

1 Claim. (Cl. 95—100)

1

This invention relates to a greatly improved rack for development of photographic films and for many other chemical processes involving the treatment of relatively thin strips of materials.

More specifically this invention relates to an improved rack which provides easy access to chemical treating materials for articles held therein. The new frame will hold individual strips out of each other's contact during processing while in wet, sticky or weakened condition thus guaranteeing a satisfactory product where proper treating methods have been followed.

While not limited thereto, the invention is of particular importance where a developing rack is desired that allows easy addition or removal of individual frame members so as to allow utilization of the device in connection with any convenient number of strips. In addition to these advantages the new device is cheap, light, easy to handle and easy to carry, and may be made on cheap and easily available equipment without trouble.

In accordance with this invention grooved members for support of the elongated strips to be treated are nested in rectangular position to provide a quadrangular structure for passage and holding of the strip to be treated. Affixed side strips, an open frame on the bottom which prevents sliding out of the strips in downward direction, and convenient handling means for supporting the frame without touching any of its members or the strips therein are provided. It will thus readily be observed that using this invention the operator need not enter the treatment tank in order to effect all the processing steps.

Various modifications illustrated in the accompanying drawings and described more in detail later on in this specification are embraced in this invention. They provide various arrangements and combinations of the frames under discussion.

For further comprehension of the invention, and of the objects and advantages thereof, reference will be had to the following description (and accompanying drawings), and to the appended claim in which the various novel features of the invention are more particularly set forth.

In the accompanying drawing forming a material part of this disclosure:

Fig. 1 is an elevational view of a treatment rack built in accordance with this invention.

Fig. 2 is a side view of Fig. 1.

Fig. 3 is a sectional view taken on line 3—3 of Fig. 2.

Fig. 4 is a section of the bottom of the rack shown in the previous figures and taken along line 4—4 of Fig. 2.

Fig. 5 is the upper part of a vertical section taken at right angles to Fig. 3 along line 5—5 of that figure.

Another modification of this invention, useful in particular where only few strips are intended to be treated simultaneously is shown in Fig. 6 which is an elevational view.

Fig. 7 is a side view of Fig. 6.

Fig. 8 is a section of the bottom of the structure illustrated in Figs. 6 and 7 and taken along line 8—8 of that latter figure.

Fig. 9 is a side section of the top of the structure illustrated in the three preceding figures and has been taken very close to one of the shorter edges.

Fig. 10 shows yet another modification of the invention in elevational front view.

Fig. 11 is a side section of the device illustrated in Fig. 10 taken close to one of its corners.

The treatment rack made in accordance with the form of the invention illustrated in Figs. 1—5, includes a plurality of grooved vertical passages 10 facing each other and rigidly held together in spaced position by a plurality of fitting short horizontal grooved members 11 and 12 which are nested in rectangular relation to the grooved vertical passages 10. Outside horizontal members 11 fit only upon one thickness of the vertical grooved passages 10 while the inside horizontal members 12 are required to fit upon two parallel walls of vertical grooved passages 10. As a relatively tight fit is required it will be readily understood that the U-shaped groove is considerably wider in grooved members 12 than in grooved members 11. Side straps 13 and 14 adhesively attached in horizontal position along the backs 40 of grooved vertical passages 10 help hold the structure together and give it added rigidity.

The lower end of the frame is held together by an open framework consisting of narrow straps so as to prevent the strips under treatment from sliding out while leaving enough open space for penetration of treating agents into the frame in an upward direction. This open framewise structure may conveniently be composed of four horizontal straps 15 together forming a square which fits tightly upon the entire bottom of this structure and held together by a pair of crossed bars 16 located at the very bottom of this construction.

A convenient handle 17, which may be U-shaped or may have any other convenient

shape is securely attached to one horizontal wall of the structure.

During operation of this device a series of strips of material to be treated are merely slid into the space between horizontal grooved members 11 and 12, or 12, and by the grooves. The device is then held at handle 17 and dipped into the treatment tank in that position. It now undergoes any desired treating process or any multitude of them. At the end of processing the strips are withdrawn in inverse manner of insertion.

The device illustrated in Figs. 6-9 is quite similar to the one discussed above, both, in operation and construction but utilizes additional grooved members 18 in vertical position to separate grooved vertical passages 10. It also has a straight handle 19 having a rounded grasp portion. In this embodiment extra wide horizontal grooved members 21 rectangularly nesting one vertically grooved member 18 and two walls of grooved members 10 at each of its ends. It should be noted from this embodiment of the invention that outside horizontal members 11, or 11 and 12, may be utilized at the bottom similar to the manner of the utilization at the top of the structure. A simple short horizontal bottom strap 20 crossing the otherwise open bottom of the frame prevents loss of materials during treatment.

In still another phase of the invention illustrated in Figs. 10-11 the horizontal grooved members are entirely dispensed with in favor of additional bottom and top straps 22 also horizontal, which cooperate with centrally located horizontal straps 13 and with trapeze shaped handle 23 to hold this structure in spaced rigid relation.

The device illustrated in Figs. 10 and 11 is quite similar to the two prior modifications of the inventions but will be of special interest where individual treatment of strips is preferred.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

5 In a holder for photographic film having a plurality of opposed aligned laterally spaced vertical channel members with the free ends of their arms directed toward each other for receiving between the arms of each aligned pair of channel members a strip of film, means at the top ends of said channel members closing the space between adjacent channel members and providing a smooth top surface for guiding strips of film into the space between the arms of each aligned pair of channel members, comprising horizontal channel members at the top ends of said first-mentioned channel members, said horizontal channel members having their free arms directed downwards and overlapping and secured to the top ends of adjacent arms of aligned pairs of said first-mentioned channel members and their intermediate arms extended across and closing the space between said adjacent arms of said aligned pairs of said first-mentioned channel members.

25 HERMAN MILLMAN.
